(57) CLAIM

The ornamental design for a baby carrier, as shown and described.

DESCRIPTION

FIG. 1 is a front view showing our new design for a baby carrier,

FIG. 2 is a rear view thereof,

FIG. 3 is a right side view thereof,

FIG. 4 is a left side view thereof,

FIG. 5 is a rear perspective view thereof,

FIG. 6 is a top view thereof; and,

FIG. 7 is a bottom perspective view thereof.

The broken lines on the surface of the carrier represent stitching.

1 Claim, 7 Drawing Sheets
